UNITED STATES PATENT OFFICE

2,134,054

RAIN DEFLECTOR

Charles W. Mabey, Lutz, Fla.

Application September 1, 1937, Serial No. 161,902

4 Claims. (Cl. 296—44)

The tops of practically all of the stream-lined automobiles now built are so curved and sloped toward the window openings as to cause rain water and even heavy dews to run down and enter the car if the windows are lowered even one or two inches.

The object of this invention is to provide a deflector capable of being applied readily as an attachment to such cars, which will shed dew or light rain when the windows are full open and which will exclude the water of a heavy rain with the windows open enough to admit fresh air on hot, rainy days, and obviously remove the worry when occupants leave their car occasioned by the fear that they have forgotten to entirely close the windows.

A further object is to provide a deflector that is inexpensive to make, that is adjustable to openings of different sizes, that is easily and quickly installed, that will not interfere with the opening and closing of the windows and that will add beauty to instead of marring the appearance of the car when installed.

I accomplish the above and other objects which will hereafter appear by the means illustrated in the accompanying drawing, in which:

Fig. 1 is a view in front elevation of my invention detached from an automobile;

Fig. 2 is a cross section on the line 2—2 of Fig. 1;

Fig. 3 is a section on the line 3—3 of Fig. 1, also showing the curved end of the deflector;

Fig. 4 is a perspective view of a clip used in fastening the deflector to the car;

Fig. 5 is a fragment of the side of an automobile showing a window with my invention operatively installed therein;

Fig. 6 is a detail in cross section on the line 6—6 of Fig. 5, and

Fig. 7 is a detail in vertical section on the line 7—7 of Fig. 5.

Like characters of reference indicate like parts in the several views of the drawing.

Referring particularly to Fig. 7, the outer plate

8 and inner plate 9 of the door frame are of steel and of usual construction. They are each lined with felt layers 10 which are generally held in place by felt strips 11. The space between the two felt strips 10, 10 forms a run for a glass window 12 slidably mounted in a manner for raising

and lowering of the window therebetween. The same double felt structure is continued across the top of the window opening. So far the construction is old and well known.

My rain deflector is installed in the top portion

of the window opening. It is substantially a sheet metal awning, with an approximate two inch projection, sloping downwardly, and in a plurality of sections longitudinally slidingly overlapping or telescoping for lengthwise adjustment to fit varying widths of window openings.

As shown in Figs. 1 to 5, there is a middle section 13, substantially U-shape in cross section as shown in Fig. 2, into which end sections 14 and 15, respectively, telescope, as shown in Fig. 5, in order to lengthen or shorten the over-all longitudinal dimensions of the deflector to fit windows of different widths.

All of the sections 13, 14 and 15, have their inner edges bent upwardly into a flange on each section which is introduced between the outer felt layer 10 of the automobile top and the outer frame plate 8, and to facilitate the insertion between the felt and plate the flanges are preferably formed into a series of individual tongues 20 indicated at 16 on the middle section 13 and at 17 on the end sections 14 and 15. The tops of these tongues are rounded to keep them from catching on the felt in the installation.

Between the tongues 16 on the middle section 13 are similar shorter and narrower tongues 18, some or all of which may be bent down against the upper leg of the U-shaped section 13 to clamp the legs together and hold the telescoped ends 14 and 15 from longitudinal displacement in an assembly.

The tongues are at angles which give a slant downwardly to the hood portions of the sections 13, 14 and 15 in order to drain off rain water that may be deposited thereon.

The outer ends of each of the sections 14 and 15 are curved downwardly as shown at 19 in Figs. 1 to 5, to fit the curved corners of the window opening and approximately at the upper ends of each of these curves the hood portions are provided with corrugations 20 as drains to carry off the water before it reaches the curves.

The front edges of the end sections 14 and 15 are bent to form a finishing bead 21.

After the deflector is installed as above provided, with the tongues between the steel frame and the felt, it is retained against road pounding and jars by steel clips 22, here shown as four in number, but more or less may be used if desired.

These clips are generally U-shape, as shown in Fig. 4, with the legs a distance apart to fit closely against and really embed themselves in the two felt strips between which the glass window is mounted, as best shown in Fig. 6. One leg 24 is extended and bent outwardly to contact the sec-

tion 13 or the sections 14 and 15, as the case may be, thereby forming a positive stop to keep the sections in place with the tongues inserted between the steel frame and adjacent felt.

5 Having thus fully described my invention, what I claim as new and wish to secure by Letters Patent of the United States, is:

1. A water deflector for automobile windows having a downwardly sloping hood and a flange 10 means at its rear edge for attachment to a window frame, in combination with spring clips having U-shape spring members sprung into engagement with the inner walls of the window guides, and each having a leg contacting the deflector 15 to prevent disengagement of the flange means.

2. In combination with a water deflector for automobile windows made in sections for adjustment as to lengths and having a downwardly sloping hood, felt engaging U-shape spring clips 20 to hold it in the frame, and frame engaging members comprising a series of tongues for individual adjustment with the hood and frame and impingement in the frame.

3. A water deflector for automobile windows slidingly mounted in felt channels, said deflector made in sections for adjustment as to lengths and having a downwardly sloping hood and frame engaging members to hold it in the frame, said frame engaging members comprising a series of tongues for impingement in the felt, and U-shape spring clips embedded into the felt and engaging the deflector to prevent disengagement of the tongues.

4. A water deflector for automobile windows, mounted in felt-lined channels and made in a plurality of sections telescoping as to length of the deflector, flange means divided into tongues for securing the sections to the window frame, 1 some of the tongues being bent over upon and against the sections to retain them in given adjustments, and others embedded in the felt and clips for preventing the disengagement of the embedded tongues.

CHARLES W. MABEY.
